UNITED STATES PATENT OFFICE.

JOHN C. VAN SLYKE, OF WASHINGTON, DISTRICT OF COLUMBIA.

ATTACHMENT FOR COTS OR HOSPITAL BEDS.

Application filed November 3, 1919. Serial No. 335,243.

To all whom it may concern:

Be it known that I, JOHN C. VAN SLYKE, a citizen of the United States, residing at Washington, in the District of Columbia, 5 have invented new and useful Improvements in Attachments for Cots or Hospital Beds, of which the following is a specification.

This invention relates to improvements in hospital cots or invalid beds, and more particularly to attachments therefor for changing the relation of the patient to the mattress of the cot or bed.

The objects of this invention are to provide a frame and covering such as disclosed 15 in my former Patent No. 985,306 and the operating means therefor, such as shown in my former Patent No. 985,307, with an improved and simplified means of attachment and operation whereby the operating cables 20 are prevented from riding over and binding on the pulley sheaves, completely covering the cables within the standards by supporting the operating means within a casing communicating with the bottom of one 25 standard, and providing means for adjustably securing the standards in fixed relation to the cot or bed structure which will not scratch nor mar the enamel or paint thereof when removed or adjusted to other structures of different sizes.

While the preferred forms of this invention are illustrated in the accompanying sheets of drawing, yet it is to be understood 35 that minor detail changes may be made without departing from the scope thereof.

Figure 1 of the drawing represents a view in side elevation of a hospital cot or invalid bed to which this improved attachment has been applied, with the central portion of the 40 bed broken away.

Fig. 2 is a view in end elevation of Fig. 1, illustrating the operating mechanism.

Fig. 3 is an enlarged detail view in side elevation of one of the pulley sheaves.

Fig. 4 is a view in front elevation of Fig. 3.

Fig. 5 is an enlarged detail top plan view of the means for attaching standards to the top rail of the cot or bed.

Fig. 6 is a view in side elevation of Fig. 5.

Fig. 7 is an enlarged detail view in end elevation of the operating mechanism with the front part of the casing broken away.

Fig. 8 is a view in side elevation of Fig. 5, with part of the side of the casing broken away.

Fig. 9 is an enlarged detail view in vertical section illustrating the tension means within a standard.

The drawing illustrates this invention as applied to an ordinary form of iron bed or cot in which the head and foot rails 1 are of tubular construction supporting between them the side and end rails 2 and 3 of ordinary form upon which the usual springs and mattress 4 rests. The canvas-covered frame 5 resting upon the mattress is preferably constructed in accordance with my former Patent, No. 985,306, in which the operating wheel 6 of the adjusting means extends 60 from the end opposite the adjustable side member 7 of the frame, thereby equally distributing the weight within the frame and causing it to balance when raised above the mattress.

Pulley sheaves 8 are rotatably mounted on the upper ends of the tubular standards 9, the casings of which communicate with the interior of the standards and are cut away in the front, as illustrated in Fig. 4, 80 and the upper wall 10 of each side of the casing extends slightly beyond the circumference of the pulley wheel 11, and this projection is provided with means, such as a connecting pin 12, which will positively 85 prevent the cable from leaving the pulley wheel and binding in the casing.

The tubular standards 9 are each secured to the top of the head and foot rails by two plates 13 and 14 embracing the standards and having on each side of the standard apertures through which hooked bolts 15 are passed with the hooked end 16 engaging the rail and the opposite end 17 extending beyond the outer plate screw-threaded and 90 adapted to receive a securing nut 18, whereby the plates are drawn together to engage the standard and the inner plate to engage the rail and maintain the standard in fixed relation thereto. The lower end of the 95 standard is secured to the end rails by a bracket 19, having a sleeve at one end and set screw for engaging the bottom of the standard, said bracket being provided with a longitudinal slot through which a hooked bolt 20 is passed, adapted to engage the end rail and having a securing nut 21 upon the lower side of the bracket.

The operating mechanism comprises a worm shaft 22 engaging a worm wheel 23 to which is attached a winding drum 24, all of which are mounted within a casing 25 car-

ried upon the lower end of one of the standards and communicating with the interior thereof. The other standard is provided with a pulley sheave 26 upon the lower end 5 thereof, which also communicates with the interior of the standard. Cables 27 and 28 for raising or lowering the frame are secured to the winding drum, one of which passes through the casing and up through 10 the standard to which the casing is attached over the pulley wheel at the top thereof, and the other passes out of the casing through an aperture provided therefor under the cot and through the pulley sheave on the 15 bottom of the other standard and thence through that standard and out over the pulley wheel at the top thereof. Both cables are secured at their free ends to slings having branches 29 and 30 adapted to be de- 20 tachably secured to the ends of the frame, as shown in Fig. 2. The worm shaft is operated by a handle 31 extending to the rear of the casing of the operating mechanism. The winding drum is provided with 25 an automatic stop and the cables are attached to the drum in such a manner that the stop will prevent further rotation as the ends of the cable approach the pulley sheaves thereby preventing the slings from striking 30 and binding in the sheaves. This automatic stop preferably comprises a pin 32 carried on the worm wheel or drum and extending from the outer side thereof, which is adapt- 35 ed to engage a rotatable stop member pivotally mounted on the interior of the side wall of the casing. This stop member com- 40 prises two arms 33 and pivot 34. The arms extend at right angles from each other and adapted to be engaged on the inner side by the pin 32 and the outer sides are adapted to alternately engage the bottom of the cas- 45 ing. By this means it is arranged that two rotations of the drum may take place in either direction before the automatic stop functions.

As seen in Fig. 8, when the drum rotates to the left the pin 32 will engage one of the arms 33 of the stop, and as the stop is pivotally mounted, it will be rotated about its 50 pivot, allowing the pin to continue in its movement and the outer side of the member of the stop so engaged will contact with the bottom of the casing as shown, bringing the other arm of the stop into a vertical position, 55 whereby upon the continued rotation of the drum the pin 32 will engage the outer side of this other arm of the stop and thereby prevent further rotation in that direction. Upon reverse movement the action just de- 60 scribed will be repeated, but in the opposite direction.

The cables are received in grooves 35 of screw-threaded form upon the drum and are secured thereto in such relation that the auto- 65 matic stop will prevent movement just be-

fore the slings upon the other ends engage the pulley sheaves.

As the cables are preferably of wire, if desired, a tension means may be employed to prevent the cables from slipping out of 70 their respective grooves upon the drum on account of the stiffness of the wire. Fig. 9 illustrates such a device, which comprises a coil spring 36 mounted in each standard resting on a stop 37 fixed to the standard 75 and engaging a sliding stop 38 secured to the cable in such relation that the cable passing over the drum is under constant tension.

It is readily seen by this construction that the frame may be raised or lowered in re- 80 lation to the mattress and, by the use of the worm shaft and wheel, the patient's weight upon the frame will cause the operating mechanism to bind or lock so that the frame will remain in fixed position.

By making the slings detachably connected to the ends of the frame, it is readily understood that by detaching both of the branches of one sling, the opposite end of the frame may be raised or lowered independently; likewise, by detaching the branches of both slings from one side of the frame, the other side may be raised or lowered independently. By mounting the sheaves on the top of the standards so that they will 95 rotate thereon, the cables are prevented from binding when one side of the frame is raised or lowered. By mounting the operating mechanism upon the bottom of one standard, the cables are not exposed at the ends of the 100 cot or bed. When it is desired to adjust the upper securing means of the standards, the nuts of the hook arms are removed, or sufficiently loosened, so that the plates may be separated and the hooks disengaged from the top rail, thus preventing sliding of the 105 attachment over the standard or the rail, which would scratch or mar the enamel or paint.

What I claim is:

1. A hoisting attachment of the character described, comprising a hollow standard; a sheave mounted at one end thereof and around which a cable is adapted to pass and through the hollow standard; a casing disposed on the other end of the standard; a drum rotatably mounted within the casing, and around which the cable is adapted to be wound; a gear associated with the drum; a driving pinion associated with the gear, being mounted in operable arrangement within the casing; operating mechanism for the driving pinion mounted outside the casing and operatively associated with the driving pinion; a portion of a stop mechanism carried by one of the rotating parts; and a bell-crank lever pivotally mounted, between the ends of the arms of the lever, upon a portion of the apparatus movable in relation to the other component of the stop mecha- 110 115 120 125 130

nism and operable to permit rotative movement of the coacting part, in one direction, to trip one of the arms of the bell-crank and pass over it, and at the same time bring 5 the other arm into the path of travel of the coacting part to act as a positive stop against movement past the arm.

2. The structure set forth in claim 1

wherein a frame, mounted on cables, is suspended from standards as set forth in the 10 claim; and means for detachably securing the standards to a hospital bed or the like, the casing being detachably mounted on the standard to be interchangeable with a sheave instead.

JOHN C. VAN SLYKE.
